UNITED STATES PATENT OFFICE.

JOHN J. ZIMMELE, OF MERCHANTVILLE, NEW JERSEY.

DESIGN FOR A HINGE-POST.

SPECIFICATION forming part of Design No. 28,891, dated June 21, 1898.

Application filed May 13, 1898. Serial No. 680,644. Term of patent 3½ years.

To all whom it may concern:

Be it known that I, JOHN J. ZIMMELE, of Merchantville, in the county of Camden, State of New Jersey, have invented and produced a new and original Design for Hinge-Posts, of which the following is a specification, reference being had to the accompanying drawings, forming part thereof.

Figure 1 is a perspective view of a hinge-post, showing two adjacent sides and the top of my new design. Fig. 2 is a perspective view showing the top and the two adjacent sides opposite to those illustrated in Fig. 1. Figs. 3 and 4 are respectively elevations of the adjacent sides shown in Fig. 2.

As shown in the accompanying drawings, the characteristic feature of my design consists of a substantially right rectangular prismatic form having an aperture A, whose faces $a a'$ are substantially parallel with the sides B C of the post and extend from the top D thereof to an enlarged cylindrical aperture

E, which extends therethrough substantially parallel with the sides B C. A second cylindrical aperture F beneath and substantially parallel with the aperture E extends through the post. A cylindrical aperture G extends through the post near the top thereof and at right angles to the faces $a a'$, and a cylindrical aperture H extends partially through the post at right angles with the aperture F and intersecting therewith.

The corners b of the top of the post are rounded, and the cylindrical spud c is formed at the base.

Having described my invention, I claim as new and desire to secure by Letters Patent—

The design for a hinge-post, substantially as shown and described.

JOHN J. ZIMMELE.
